TOY WHEEL CENTER DISC

William H. Edwards, 25 Blythewood Drive,
Greenville, S.C. 29607

Filed Jan. 3, 1967, Ser. No. 5,273

Term of patent 14 years

(Cl. D34—15)

The sole figure of the drawing is a side elevational view of a substantially flat toy wheel center disc embodying my new design.

The phantom line showing of the wheel portion in the drawing is for illustrative purposes only.

The side not shown is substantially identical in appearance and configuration to the side shown.

I claim:

The ornamental design for a toy wheel center disc, as shown and described.
